PLUTONIUM PURIFICATION PROCESS EMPLOYING THORIUM PYROPHOSPHATE CARRIER

Edward L. King, Madison, Wis., assignor to the United States of America as represented by the United States Atomic Energy Commission

No Drawing. Application February 7, 1949
Serial No. 75,063

4 Claims. (Cl. 23—14.5)

This invention relates to the separation and purification of plutonium and particularly to the separation of plutonium from radioactive elements of lower atomic weight.

In this specification and claims, the name of the element designates generically the element both in its free state and combined in a compound. The element in its free state is designated by the term "elemental" or by its specific state, such as "metallic."

An object of the present invention is to provide a method for separating plutonium from certain elements with which it is contaminated as a result of its formation by the neutron irradiation of uranium.

Additional objects and advantages of this invention will be evident from the following description.

It has been found that plutonium ions in the tetravalent state may be separated from an aqueous solution by precipitating the tetravalent plutonium ions with pyrophosphate anions. It has further been found that tetravalent plutonium ions contained in an aqueous solution in a concentration so low that said plutonium ions will not be precipitated directly as the pyrophosphate may be removed substantially quantitatively from the solution with a carrier precipitate of certain pyrophosphates which are insoluble in aqueous solutions. The pyrophosphates which have been found to be most useful as plutonium carriers include the uranous, ceric, zirconium, and particularly thorium pyrophosphates. These carrier pyrophosphates, for example thorium pyrophosphate, have been found to carry tetravalent plutonium ion quantitatively but do not carry the trivalent or hexavalent plutonium ion, the trivalent rare earth ions or the uranyl ion from aqueous acidic solutions. The process of this invention is based upon the foregoing discoveries. Broadly, this process comprises forming an aqueous acidic solution of plutonium ions in the tetravalent state and elements with which it is normally contaminated in neutron irradiated uranium, treating this solution with a soluble thorium compound and a soluble pyrophosphate compound whereby a carrier precipitate of thorium pyrophosphate is formed in said solution, separating the thorium pyrophosphate precipitate together with the tetravalent plutonium carried with said precipitate, dissolving said precipitate, reducing the tetravalent plutonium ions contained in the new solution to the trivalent state, and re-precipitating the thorium pyrophosphate, leaving the trivalent plutonium ions in the solution in a substantially pure state.

This process is not only useful in obtaining plutonium in an uncontaminated state but is also useful in obtaining radioactive fission products. The usefulness of these radioactive fission products as tracers and as therapeutic agents is well known.

The plutonium may be placed in solution by dissolving a neutron irradiated uranium mass in an aqueous solution of a strong inorganic acid or a highly ionized organic acid, which does not form complexes with heavy metal ions. In general, nitric acid and hydrochloric acid

2

are to be preferred, although sulfuric acid may be used if consideration is given to the tendency of sulfuric acid to form plutonium complexes. It will also be apparent that certain acids are excluded depending upon the choice of cation for the carrier precipitate. Thus, if thorium pyrophosphate were to be used as a carrier, an acid would not be chosen which would form an insoluble compound with thorium. Other considerations, such as the formation of complex ions may exclude other acids in certain instances. However, nitric acid and hydrochloric acid are highly satisfactory in all cases and it is unnecessary to attempt to use other acids for the adjustment of the pH of the solution. After the plutonium is brought into solution, the acidity of the solution is adjusted within broad limits, for example from 0.5 to 5 N, but preferably between about 0.5 and 2 N. It is essential that the solution be acid prior to the precipitation step if the plutonium is to be separated from trivalent rare earth contaminants by the precipitation since the trivalent rare earth pyrophosphates are insoluble in alkaline or neutral solution. The precipitate should not be permitted to remain in contact with acid solutions for long periods of time since the precipitate may be hydrolyzed, but this effect is very slow at room temperature.

It is important that the plutonium be present in the solution in the tetravalent state since it has been found that only the tetravalent plutonium ion forms an insoluble pyrophosphate in acid solutions. Relatively stable states of plutonium in the ionic state in aqueous solution are the +3, +4, and the +6 states. The normal state of plutonium when it is placed in solution by the dissolving of neutron irradiated uranium in nitric acid or hydrochloric acid is the +4 state, so that if the solution is formed in this manner, ordinarily, no further precautions need be taken to insure that the plutonium is in solution in the tetravalent state. However, should the plutonium be placed in solution by any other method which would make the valence state of the plutonium questionable, the plutonium may be treated with suitable oxidizing or reducing agents, as the case may be, to insure that it is in the tetravalent state. The oxidation-reduction potentials (referred to the normal hydrogen electrode) linking Pu^{+3} , Pu^{+4} , and Pu^{+6} in 1 M nitric acid at 30° C. are:

Pu^{+3}	—0.92 volt	Pu^{+4}	—1.11 volts	Pu^{+6}
			1.04 volts	

By referring to a table of oxidation and reduction agents with their respective potentials, such as given by Latimer and Hildebrand in the Handbook of Chemistry and Physics, suitable agents may be chosen to treat the plutonium contained in solution to insure that it is present in the tetravalent state.

The removal of the tetravalent plutonium from the solution with a carrier may be effected by the precipitation of the carrier in the solution, by the treatment of the solution containing plutonium with the preformed carrier, or by passing the solution through a bed of the carrier. However, it has been found preferable to form the carrier in the solution. This may be done by introducing a soluble compound containing the cation, for example thorium chloride or thorium nitrate where thorium pyrophosphate is to be the carrier, into the solution. The carrier precipitate may then be formed by introducing a soluble pyrophosphate compound, such as potassium or sodium pyrophosphate or pyrophosphoric acid into the solution. The order or method of contacting the plutonium-containing solution with the carrier is not essential and variations may be introduced

without departing from the method of the invention. The pyrophosphate carriers herein described are soluble in an excess of pyrophosphate, presumably by the formation of pyrophosphate complexes, such as thorium pyrophosphate complex. Although a precipitate of thorium pyrophosphate can be formed where the molarity of the pyrophosphate in solution is ten times as great as the molarity of the thorium, it is desirable to form the carrier pyrophosphate in a solution where the molarities of the cation and of the pyrophosphate do not differ too greatly from stoichiometric proportions. It is, of course, desirable to maintain the concentration of free pyrophosphate ion in solution at a minimum during the precipitation step. It has also been found desirable to carry out the carrier precipitation at room temperature particularly if the solution contains nitric acid, since the nitric acid solution may oxidize the Pu^{+4} ions at elevated temperatures. Precipitation is usually complete with relatively short periods of digestion even at room temperature. The thorium pyrophosphate-plutonium pyrophosphate precipitate is a white crystalline precipitate and it may be separated from the solution by filtration, decantation, or preferably centrifugation.

This step of precipitating tetravalent plutonium with a pyrophosphate carrier may be used to separate plutonium from most elements with which it is contaminated, except those which are normally tetravalent in aqueous acidic solution. Thus, this step will separate plutonium from the rare earths (including cerium, which will normally be present in aqueous solution in the trivalent state), Rb, Sr, Y, Cs, Ba, Kr, and Xe. This step may also be used to separate plutonium from uranium because by the normal process of dissolving neutron irradiated uranium in nitric acid, the uranium is present in the uranyl nitrate hexahydrate thus formed, in the hexavalent state in which state it is not carried with the ThP_2O_7 - PuP_2O_7 precipitate. This step of the process may also be used as an analytical procedure to determine the relative amounts of trivalent, tetravalent, and hexavalent plutonium in solution, since the tetravalent plutonium will be carried with a pyrophosphate precipitate, while the trivalent and hexavalent plutonium will remain in solution.

Following the separation of the ThP_2O_7 - PuP_2O_7 precipitate, the precipitate is placed in solution. This may be accomplished by a treatment of the precipitate with an excess of pyrophosphate ion. For example, the thorium-plutonium pyrophosphate may be introduced into a pyrophosphoric acid solution or into a solution of an alkali metal pyrophosphate wherein the free pyrophosphate ion is in considerable excess with respect to the combined amount of plutonium and thorium pyrophosphates. Following the dissolution of the carrier precipitate, the plutonium is reduced to the trivalent state. The choice of reducing agents will depend to some extent upon the concentrations of the reactants, and upon the effect of the reducing agent and products thereof upon the solubilities of the ions present. As to the potentials required of the reducing agent, it has been found that where the concentration of the pyrophosphate ion is in the vicinity of 0.1 m, a reductant having a potential more positive than about -0.8 volt reduce the tetravalent plutonium present in the plutonium pyrophosphate complex, to the trivalent state. Under any conditions of concentration normally encountered in this process, reducing agents having a potential more positive than about -0.4 volt will accomplish the reduction of the tetravalent plutonium. The effect of the reductant and reduction products upon the solubilities of ions present may readily be determined by consulting standard tables of solubilities. Representative examples of reducing agents which have been found to be suitable are hydroxylamine, hydrogen peroxide, and oxalate ions. Following the reduction of the plutonium to the trivalent state the ions of the original carrier are again precipitated from the solu-

tion by introducing a soluble compound containing the carrier cation into the solution so that the ratio of carrier cation to pyrophosphate anion approaches stoichiometric proportions. The precipitate thus formed is then separated from the solution by any suitable method. This step not only frees the plutonium from the carrier but is also effective in increasing the decontamination of the plutonium. For example, zirconium, which ionizes only in the tetravalent state and which may be carried by the

10 original carrier, will be removed from the solution containing plutonium by this second precipitation step. Thus, this method proves an effective separation process for separating plutonium from zirconium. Even fission products having tetravalent and lower oxidation states may be separated from plutonium by this step of the process by the suitable selection of a reducing agent so that the plutonium but not the fission product is reduced from the tetravalent state. Thus, in the final step plutonium will be reduced to the non-carriable state with 15 pyrophosphate but the fission product will not be reduced and will be carried from the solution with the pyrophosphate carrier. Decontamination of plutonium by this process may be increased indefinitely by performing this process as a cycle and repeating the cycle. Following the 20 re-precipitation of the carrier precipitate, the plutonium may be oxidized to the tetravalent state, thus completing a cycle and the entire cycle may be carried out as often as desired.

25 This invention will be further illustrated by the following specific example.

Example

30 Four hundred fifty micrograms of $Th(NO_3)_4$ and 600 micrograms of $LaCl_3$ were dissolved in 1 M HCl. Tracer quantities of $Pu(NO_3)_3$ and $Pu(NO_3)_4$ were introduced into this solution. Two hundred sixty-six micrograms of $Na_4P_2O_7$ were then introduced into an aliquot of the above solution having a final volume of 0.12 ml. A white crystalline precipitate formed and this was digested at 35 room temperature with stirring for eight minutes. This precipitate was then separated from the solution by centrifugation. The solution and the precipitate were analyzed by radiometric methods and it was found that 40 98.4% of the tetravalent plutonium had carried with the ThP_2O_7 . More than 99% of the trivalent plutonium and more than 99% of the lanthanum remained in the solution. Following the separation of the ThP_2O_7 plutonium carrier precipitate from the solution containing the lanthanum and trivalent plutonium, the precipitate is 45 dissolved by introducing the precipitate into 0.15 ml. of 0.1 M $Na_4P_2O_7$ and digesting at 60° C. for approximately one hour. Following the dissolution of the precipitate the tetravalent plutonium is reduced to the trivalent state by treatment with hydroxylamine hydrochloride. The solution is then contacted with 2800 micrograms of Th^{+4} (as the chloride), thus causing a precipitate of ThP_2O_7 to form. This precipitate is digested for 50 ten minutes at room temperature with stirring and then separated from the solution, leaving the trivalent plutonium in solution. Analysis of the precipitate discloses that less than 2% of the plutonium carries with the precipitate.

55 It is to be understood, of course, that the above example is merely illustrative and does not limit the scope of this invention. Other mixtures of plutonium with elements of lower atomic numbers may be employed as starting materials and other acids and other cations may be substituted for those of the above example, within the scope of the foregoing description. Likewise, the 60 process of the example may be modified by incorporating other purification steps in addition to the use of the steps previously described. In general, it may be said that the use of any equivalents or modifications of procedure which would naturally occur to one skilled in the 65 art is included in the scope of this invention. Only

such limitations should be imposed on the scope of this invention as are indicated in the appended claims.

What is claimed is:

1. A method of purifying plutonium, which comprises adding a soluble thorium compound and a soluble pyrophosphate compound to an aqueous acidic solution of tetravalent plutonium, separating the ThP_2O_7 — PuP_2O_7 precipitate thus formed from the solution, dissolving said precipitate, adding to the solution thus formed a reducing agent having a potential more positive than about —0.8 volt, whereby the tetravalent plutonium is converted to the trivalent state, precipitating ThP_2O_7 in the resultant solution and separating said ThP_2O_7 from the solution of trivalent plutonium.

2. A method of separating plutonium from elements with which it is normally contaminated in neutron irradiated uranium, which comprises forming an aqueous acidic solution containing said plutonium in the tetravalent state and contaminants, adding a soluble thorium compound and a soluble pyrophosphate compound to said solution, the pyrophosphate compound being approximately stoichiometrically equal to the thorium and other tetravalent ions in said solution, separating the ThP_2O_7 — PuP_2O_7 precipitate thus formed from the solution, dissolving said precipitate, adding to the solution thus formed a reducing agent having a potential more positive than about —0.8 volt, whereby the plutonium is converted to the trivalent state, precipitating the ThP_2O_7 and separating said ThP_2O_7 precipitate from the solution containing the trivalent plutonium.

3. A method of separating plutonium from zirconium, which comprises forming an aqueous acidic solution containing said plutonium in the tetravalent state and zirconium, adding a soluble thorium compound and a

soluble pyrophosphate compound to said solution, the amount of said pyrophosphate compound being approximately stoichiometrically equal to the combined amount of thorium, plutonium, and zirconium ion present in the solution, separating the ThP_2O_7 — PuP_2O_7 — ZrP_2O_7 precipitate thus formed from the solution, dissolving said precipitate, adding to the solution thus formed a reducing agent having a potential more positive than about —0.8 volt, whereby the plutonium is converted to the trivalent state, precipitating ThP_2O_7 — ZrP_2O_7 and separating said precipitate from the solution containing the trivalent plutonium.

4. A method of separating plutonium from radioactive fission products, which comprises forming an aqueous solution containing said plutonium in the tetravalent state and fission products, adjusting the acidity of said solution to between 0.5 and 2 M, dissolving in said solution a soluble thorium compound, introducing $\text{Na}_4\text{P}_2\text{O}_7$ into the solution in amount approximately stoichiometrically equal to the plutonium and thorium ions present in said solution, separating the

precipitate thus formed from the solution, introducing said precipitate into a pyrophosphate solution wherein pyrophosphate is in sufficient concentration to dissolve the precipitate, adding to the solution thus formed hydroxylamine whereby the plutonium is converted to the trivalent state, introducing sufficient additional soluble thorium compound in the solution to precipitate the thorium ion in the solution as ThP_2O_7 and separating said precipitate from the solution containing the trivalent plutonium.
